UNITED STATES PATENT OFFICE

2,480,733

POWDER DISPENSING CONTAINER

Louis Hermani, Baltimore, Md., assignor to Continental Can Company, Inc., New York, N. Y., a corporation of New York

Application June 1, 1945, Serial No. 597,098

1 Claim. (Cl. 222—560)

1
The invention relates generally to container structures and primarily seeks to provide a novel container of simple and attractive design which can be economically manufactured and employed in the packaging and dispensing of powdered substances.

In the manufacture of containers of the character stated problems have been presented in developing powder dispensing containers which are substantially sift proof and yet of such simple design as to permit economical manufacture. Many containers have been designed for the dispensing of powdered substance, but no such container of which I am presently aware provides the desired qualities of simplicity in design and efficiency in the way of being proof against inadvertent sifting. The container structure of the present invention has been designed to fill these needs.

In its more detailed nature the invention has for an object to provide a container of the character stated having a convex raised portion equipped with a dispensing opening, an elongated slide held throughout its length in contact with the raised portion against resiliency inherent therein tending to straighten the same, thereby to provide tight yieldable contact between the slide and raised portion at and adjacent to the dispensing opening, and a finger piece attached to the slide by manipulation of which the slide may be moved to uncover or cover said opening.

Another object of the invention is to provide a container structure of the character stated in which the convex raised portion has parallel straight sides forming side guides for the lateral edge portions of the elongated slide.

With the above and other objects in view that will hereinafter appear, the nature of the invention will be more clearly understood by reference to the following detailed description, the appended claim, and the several views illustrated in the accompanying drawing.

In the drawings:

Figure 1 is a perspective view illustrating a container embodying the invention.

Figure 2 is a plan view of the dispensing top or breast of the container with the invention embodied therein.

Figure 3 is a vertical longitudinal section

2
through the breast structure illustrated in Figure 2, the slide being shown in the dispensing opening closing position.

Figure 4 is a view similar to Figure 3 with the slide moved into position for exposing the dispensing opening.

Figure 5 is a vertical cross section taken on the line 5—5 on Figure 3.

Figure 6 is a detail vertical longitudinal section illustrating the slide and the attaching rivet or finger piece before they are assembled on the breast.

In the example of embodiment of the invention herein disclosed, the container includes a body 5 of well known form which is oval in horizontal cross section and is closed at its lower end by a suitably attached end closure 6. At its upper end the body is provided with the usual outwardly bent bead 7 which is spaced a distance below the open top of the container body.

To the top of the container is secured the usual breast generally designated 8. The breast preferably is drawn from a single piece of metal to include the flat top portion 9 and a depending skirt 10 adapted to frictionally embrace the top portion of the body 5 above its bead 7. The breast also is formed to include a convex raised portion 11 defined at the sides by upright straight wall portions 12 arranged in parallel spaced relation in the manner clearly illustrated in Figures 1, 2 and 5.

The convex radial surface 11 embossed on the top of the breast 8 is equipped with a longitudinal slot 13 and a transverse dispensing opening

35 14. A rectangular shutter or valve slide 15 preferably formed of spring brass and which normally is flat as illustrated in Figure 6 is held against the inner face of the raised portion 11 by a rivet or finger piece 16 the shank of which passes through the slot 13 and through an aperture in the slide and is upset as at 17 beneath said slide.

It will be apparent that by forming the slide 15 of a piece of spring brass which is normally flat, and then securing the same against the curved surface of the raised portion 11 in the manner clearly illustrated in Figures 3, 4 and 5, the inherent tendency of the slide to straighten out to the normal position illustrated in Figure 6 will cause the same to engage in tight frictional contact against the undersurface of the raised

portion 11, thereby assuring against inadvertent sifting of powdery material between the slide and the raised portion 11 and out through the dispensing opening 14.

It will be apparent by reference to Figures 2 and 5 of the drawings that the long side edges of the rectangular slide 15 are effectively guided by the parallel upright wall portions 12. The rivet or finger piece 16 constitutes the wall means for holding the slide against the convex, outwardly projecting wall portion 11, and by forming the slide of a normally flat and straight piece of spring brass as shown in Figure 6 and attaching the same to the convex portion of the breast in the manner stated, it is unnecessary to provide any spring means for constantly holding the slide in tight contact with the raised portion 11 of the breast.

It will be apparent that by manipulating the member 16 as a finger piece, the slide may be moved back and forth within the limits of movement afforded by the slot 13 for closing the dispensing opening 14 in the manner illustrated in Figure 3, or for exposing said opening in the manner illustrated in Figure 4 to permit dispensing of substance from the container through said opening.

While the breast is herein shown as equipped with a dispensing opening which is rectangular and transversely disposed, it is to be understood that the opening may be shaped differently, or a plurality of small apertures may be provided if desired. It will also be readily apparent that apertures may be provided in the slide for cooperating with a large dispensing opening of any given shape formed in the convex portion 11 of the breast.

While one form of the invention has been shown for purposes of illustration, it is to be clearly understood that various changes in the details of construction and arrangement of parts may be made without departing from the spirit and scope of the invention as defined in the appended claim.

I claim:

A dispensing top for containers comprising, a

one-piece drawn breast having a horizontal flat top portion and a convex radial surface projecting upwardly from said flat top portion and merging smoothly at its ends, without shoulder projections, into said flat top portion and defined in part by spaced vertical parallel side wall portions merging into said flat top portion, said surface having a dispensing opening therein and an elongated slot, and a very thin and resilient elongated rectangular slide normally flat over its full length and breadth and movable over the interior of said surface for exposing or closing over said opening and held throughout its entire length and breadth in full surface contact with said surface against its inherent tendency to flatten out by a single rivet attached thereto intermediately of the ends thereof and passed through said slot and engaging the exterior of said surface, side edge portions of said slide extending full length in close proximity to and being guided by said parallel side wall portions so as to be held by said side wall portions against turning askew, the inherent tendency in said slide to flatten out being effective to cause the end portion thereof adjacent said opening to engage in very tight contact with said surface adjacent to and over said opening.

LOUIS HERMANI.
